UNITED STATES PATENT OFFICE

2,457,621

THERMOSTATIC ELECTRICALLY HEATED
COMB

Paul Aeris, New York, N. Y.

Application August 5, 1946, Serial No. 688,545

1 Claim. (Cl. 219—21)

1
This invention relates to combs and more particularly to an electrically heated comb.

An object of this invention is to provide an electrically heated comb having a thermostat and a thermostat control whereby the temperature of the comb may be selectively controlled by an operator for any temperature within the range of the thermostat and heating element.

Another object of this invention is to provide an improved electrically heated hair straightening comb having a selective temperature control whereby the comb may be properly used on soft or hard grades of hair without damage to the head or scalp by selecting the desired temperature.

Still another object of this invention is to provide an improved electrically heated comb of the kind to be hereinafter described having a bi-metal thermostat for breaking the electric circuit and holding the temperature at a constant selected temperature.

With the above and other objects in view, my invention consists in the arrangement, combination and details of construction disclosed in the drawings and specification, and then more particularly pointed out in the appended claim.

In the drawings,

Figure 1 is a vertical section through my electrically heated comb.

Figure 2 is an enlarged fragmentary section taken on the line 2—2 of Figure 1.

Figure 3 is a rear elevation of the handle and control knob.

Figure 5 is a diagrammatic view, partly in section, of the control cam, taken on the line 4—4 of Figure 2.

Figure 5 is a vertical section, partly broken away, taken on the line 5—5 of Figure 1.

Figure 6 is a wiring diagram of the electrical circuit.

Referring to the drawings, the numeral 10 designates generally an electrically heated hair straightening comb constructed according to an embodiment of my invention.

Heretofore there have been introduced onto the market electrically heated combs for straightening hair which have met with little commercial success for various reasons, one particular reason being that the combs were designed for a constant temperature with no means for changing that temperature, thereby limiting the use of that particular comb to one certain type of hair. A beautician would have had to equip his shop with several different combs, each having a different temperature setting, in order to properly work on various types of hair.

2
As temperature on the head and hair for such treatment is of critical consideration, it is important that some control be devised for selecting a maximum temperature for each time the comb is used, which temperature will be governed by the grade of hair, and will vary for each. On the heating comb 10 of my invention, I have provided such means whereby the beautician may select the highest temperature he desires the comb to reach for each grade of hair, while still keeping the size of the comb down to a readily handled size and weight.

The heater comb 10 comprises a comb 11, a handle 12, a heating element 14, and a thermostatic control switch 15 connected into the electric circuit of the heating element 14. The comb 11 is formed of a plurality of teeth 16 in the conventional manner and is a thickened body portion 17 from which the teeth 16 depend. The body 17 is formed with a bore 18 extending substantially the length of the comb 11 and opening at one end. The heating element 14 is of elongated tubular configuration and is adapted to be fixed in the bore 18 for heating the comb 11. The comb 11 may be made of bronze, iron, aluminum, plastic, or other suitable material.

A wooden handle 12 is attached to the comb 11 at one end thereof by a tube 19 which extends through the handle 12 and outwardly from the handle at one end where it is threaded exteriorly for engaging in the enlarged threaded open end of the bore 18. The tube 19 may be made of brass or any other suitable substantially rigid material and is hexagonal in section in the preferred form so that it will not be rotatable in the handle 12.

Fixed in the extending end of the tube 19 is a thermostatically controlled switch 15 for selectively controlling the temperature of the heating element 14. The thermostat 15 comprises a short section of tube 20 which is made of porcelain or other suitable non-conducting material having an outer end wall 21, in which a metal connector plug 22 is fixed and extends therethrough. A screw 24 engages in the outer end of the plug 22 for attaching a conducting wire lead 25 from the heating element 14 to the thermostat 15. A bi-metal contact supporting member 26 is carried by the plug 22 and extends within the tube 20, and a platinum or other suitable contact point 27 is carried on the member 26 at its innermost free end on the upper side thereof. The member 26 is so constructed and positioned that heat on the member 26 will cause it to be deflected or bent outwardly 55 towards the walls of the tube 20.

A short section of tube 28 is fixed in the tube 19 within the handle 12 as by a screw 29 extending through the handle 12, tube 19 and into the tube section 28. The tube 28 is formed with thick walls being threaded internally and a control rod 30 engages through the tube section 28 so the rod 30 is threaded therethrough. A plug 31, rotatable in the tube 19 at the rear end of the handle 12, is fixed on the rod 30 for supporting the rear end thereof in alignment with the sleeve 28. The forward end of the rod 30 is formed of a reduced diameter section 32 and a terminal section 35 is secured thereon to which a wire 36 is fastened which connects to the source of electric supply. The contact point 37 is fixed to the end of the rod 30 within the sleeve 20 for engaging with the contact 27 to complete the electric circuit.

The contact 37 may be fixed on the rod 30 by a force fit or other attaching means. The contact 37 is formed of a spiral shaped cam whereby the contact 37 may engage the contact 27 on the periphery thereof in such manner that the point at which the deflection of the member 26 breaks contact may be controlled by rotating the contact 37. When little heat is desired, the lowest point of the cam 37 engages the contact 27 whereupon a slight deflection of the member 26 will break the electric circuit and keep the temperature at this low value. For greater temperature, the cam 37 is rotated so the higher edges of the cam 37 engage the contact 27 in order that a large deflection of member 26 is required to break the circuit, the deflection being proportional to the temperature of the comb and thermostat.

As one complete revolution of the cam 37 comprises the entire range of adjustment, it is necessary only to provide for rotating the shaft 30 one revolution. Stop nuts 39 on the shaft 30 on each side of the sleeve 28 are provided for limiting the travel of the sleeve to one complete revolution.

An indicating pointer arm or radially extending index 40 is carried by the plug 31 outwardly of the handle 12 and the plug 31 is secured on the shaft 30 by a nut 41. A flanged sleeve 42 is engaged in the rear end of the handle 12 about the sleeve 19, the flange comprising the rearmost end of the handle 12. Indicia 44 are provided on the rear side of the plug 42 and the index 40 cooperates with the indicia 44 for indicating the rela-

tive position of the cam 37 and the relative temperature of the comb 10. The plugs 31 and 42 may be made of plastic or other suitable material.

The handle 12 is formed with a groove 45 adjacent the sleeve 19 through which the lead wires 36 and 46 may be extended. The wire 36 connects the thermostat point 37 to the source of electric power and the wire 46 connects the other end of the heating element 14 to the electric power source. The wires 36 and 46 may be enclosed in glass or other nonconducting tubes to insulate them from contact with other metal parts.

I do not mean to confine myself to the exact details of construction herein disclosed, but claim all variations falling within the purview of the appended claims.

What I claim is—

20 An electrically heated comb comprising a comb, a handle for said comb having a longitudinal bore extending therethrough, a heating element in said comb, and a heating element temperature control including a bi-metallic element connected at one end thereof in the circuit of said heating element and having a contact point on the other end thereof, a block fixed in said handle bore, a control rod in said bore threadably engaging and extending through said block, a second contact 25 consisting of a spiral cam fixed on the inner end of said control rod adjacent to said first contact, and stops carried by said control rod and adapted to engage said block for limiting the rotation of said spiral cam whereby rotation of said control rod and said cam controls the separation of said contacts upon deflection of said bi-metallic element thereby selectively controlling the temperature of said heating element and said comb.
